INFANT PROTECTOR

Clifford R. Jacobs, R.F.D. 1, King George Road,
Bound Brook, N.J.

Filed July 17, 1959, Ser. No. 56,832

Term of patent 14 years

(Cl. D5—5)

(Granted under Title 35, U.S. Code (1952), sec. 266)

The invention shown herein may be manufactured and used by or for the Government of the United States of America for governmental purposes without the payment to me of any royalty thereon.

The drawing is a perspective view of the infant protector constituting my invention. The end not shown is exactly like the illustrated end. The left hand side of the protector which is not completely illustrated consists of two filter pads exactly like the one illustrated on the right side next to the clear plastic window. The dotted line showing of an infant is for illustrative purpose only.

I claim:

The ornamental design for an infant protector, as shown and described.
